YORK.

MUSTARD-DISPENSING DEVICE.

Application filed June 21, 1926. Serial No. 117,243.

This invention relates to a device for dispensing mustard or other substance of like nature and has for its object to provide an article of this character which will obviate 5 the use of the insanitary containers in use at the present time. It is well known that in restaurants, refreshment stands and other places, mustard is usually contained in open jars or similar containers which permit the 10 air to reach the contents and cause the mustard to thicken or corrode about the mouth of the jar, at the same time permitting dirt and dust to have free access to the contents. These conditions usually cause the mustard 15 container to assume an encrusted, insanitary and unappetizing appearance.

It is the object therefore, of our invention to provide a container from which a desired amount of mustard can be dispensed when 20 required and in which the contents of the container are kept covered and unaffected by air or exterior conditions.

It is well understood that it is extremely difficult to dispense mustard in the small 25 amounts required for use upon sandwiches, sausages and the like, as the same is extremely adherent and does not flow very freely. Through the use of our invention, however, positive feeding means is presented 30 which forces the mustard out of its container in the proper amounts for application to the article of food.

Our improved container is found particularly desirable and useful at refreshment 35 stands and restaurants where sausages, sandwiches and the like are sold as it permits the mustard to be directly applied in the right quantities to the articles, obviating the use of insanitary mustard encrusted spoons, 40 sticks or the like.

With these objects and such other objects as may hereinafter appear, in view, we have devised the particular arrangement of parts hereinafter set forth and more definitely pointed out in the claims appended 45 hereto.

Reference is to be had to the accompanying drawing, in which

Figure 1 is a vertical sectional elevation of our improved container and its operating 50 parts;

Figure 2 is a sectional view on the line 2-2 of Figure 1, looking in the direction of the arrows;

Figure 3 is a sectional view on the line 55 3-3 of Figure 1, looking in the direction of the arrows; and

Figure 4 is a vertical sectional view of the lower end of the container showing the parts 60 in the act of ejecting mustard from the outlet opening in the vessel.

Throughout the various views of the drawings, similar reference characters designate similar parts.

In the accompanying drawing, 1 indicates 65 the body of the container which holds a supply of mustard. Said container may be made of glass, porcelain, china or of any other suitable material which is not affected by the mustard or such other contents as 70 may be placed within it. The body of the container may be of any desired shape and it can be supported upon suitable brackets or held upon a suitable stand of any sort for the convenience of the users. 75

The lower end of the container is preferably contracted as at 2, which provides a narrow cylindrical piston-containing chamber within which a piston member 4 is operative. Said piston 4 is arranged to fit snugly 80 within the chamber 2 and provide a good sliding fit therein. The piston 4 is provided with a series of perforations 5 extending through it which act to feed mustard to the lower part of the chamber 2 for subsequent ejection through the outlet opening 3 provided in the lower end of the chamber 2. 85

The piston 4 is securely mounted upon a vertically extending rod 6 which passes up through the container 1 and through the 90 cover 12 on the upper end of the container. Said cover 12 may be threaded upon the upper end of the container 1 or secured therein by a bayonet joint or any other type of detachable fastening means. 95

The upper end of the rod or stem 6 termin-

nates in a knob 13 adapted to be engaged by the hand of the user for actuating the piston to force mustard out through the outlet opening 3 upon a sausage, sandwich or other article. The stem or rod 6 and consequently its attached piston 4 is normally thrust upward by the impulse of a spring 10 which bears against a stop 9 secured on the rod and which is contained within a casing 11 secured to the underface of the cover 12.

At 8 is shown a disk-shaped plate which is provided with a central opening 14, through which the rod or stem 6 passes. Said opening 14 in the disk 8 is larger in diameter than the stem 6 so that the disk is therefore loosely held upon the stem 6 and is free to slide thereon as required. Said disk 8 is prevented from falling free of the stem 6 by an abutment in the nature of a nut 7 or similar stop.

It will thus be seen that the disk 8 is located between the underface of the piston 4 and the stop 7, the space between these two elements being sufficient to allow the disk considerable movement so that when said disk is in the position shown in Figure 1 and is away from the underface of the piston 4, mustard can freely move through the perforations in the piston and pass down in the chamber 2 towards its outlet opening 3. Said outlet opening 3 is preferably provided in a thickened end part of the chamber 2 so that said opening 3 is of considerable depth and the mustard must be forced through it with some pressure and thus greater quantities of mustard will not be removed from the container than are required for application to an article of food. The depth of the outlet opening 3 thus provided, aids considerably in the pumping action of the device in feeding mustard below the piston with subsequent ejection thereby.

From the foregoing, the operation of our improved device will be readily understood. Assuming that the device is filled, or partly filled with mustard. Under the impulse of the spring 10, the stem 6 is moved upwardly and its attached piston 4 is consequently moved upward in the chamber. When this occurs, mustard is forced through the openings 5 in the piston 4 and the same oozes downward past the edge of the disk 8 and into the lower part of the chamber 2. The outlet opening 3 is so minute and its depth is so great that the mustard, which flows extremely sluggishly, will not drip out and consequently, no closure means for the opening 3 is required.

To eject mustard from the container out of the opening 3, the knob 13 on the end of the stem 6 is simply pressed downward and the mustard in the lower end of the compartment 2, and which was subsequently fed thereto by the upward movement of the

piston as shown in Figure 1, is forced through the opening 3 as shown in Figure 4.

It will be seen that the pressure of the mustard in the lower part of the chamber 2, which mustard is indicated at 15, against the underface of the disk 8, causes said disk to be moved upwardly against the underside of the piston 4 to cover the openings 5 therein. Thus, when the piston 4 is moved toward the outlet opening 3, the same is completely closed and acts effectively as a plunger against the mustard 15, to force the same through the opening 3 in small quantities as are required for application to a sausage, sandwich or the like.

It will be seen also that the piston in moving either to or from the outlet opening 3 tends to force mustard towards said opening through the said piston as it moves away from the opening, feeding mustard below it and into the chamber 2 and as it moved toward the opening, it tends to force the mustard out of the opening on the article of food which is held beneath said opening 3. The upward movement of the piston is limited by means of the stop 9 on the rod or stem 6 and if desired, the spring 10 may be omitted so that the operator need give a reciprocating motion to the stem by first raising it and then forcing it down to eject the mustard.

As the device is completely closed, except for the tiny opening 3 through which the mustard is forced, there is no tendency for the mustard to corrode or encrust about the container, the same presenting an extremely neat and sanitary appearance at all times.

Having described our invention, what we claim is:

1. An article of the class described comprising a vessel for containing mustard or a like viscous substance, said vessel being provided with a narrowed lower end having an exit opening leading exteriorly of the vessel, a piston movable in said lower end and adapted by its reciprocation to directly eject the contents of the vessel through said opening and out of the vessel, a rod on which said piston is mounted, said piston being composed of a pair of disks, one of said disks being fixedly secured on said rod and being provided with a plurality of perforations, the other disk being movably mounted on the rod, said movable disk being imperforate and of less diameter than the fixed disk.

2. An article of the class described, comprising a vessel for containing mustard or the like, said vessel being provided with an integrally formed contracted lower end provided with an exit opening leading exteriorly of the vessel, a stem extending through the vessel and projecting into the contracted lower end, means on said stem moving in said contracted end for directly ejecting

mustard through the exit opening and exteriorly of the vessel, said means comprising a disk fixedly secured on said stem and fitting into the contracted end with a piston fit, said disk being provided with a plurality of perforations, and a disk movably mounted on said stem below the fixed disk, said mov-

able disk being imperforate and of smaller diameter than the fixed disk.

Signed at the city, county and State of ¹⁰
New York, this 19th day of April, 1926.

JOSEPH G. COFFIN.
